United States Patent Office

Des. 214,815
Patented July 29, 1969

214,815

HOUSING FOR A TYPEWRITER

Carl Auboeck, Vienna, Austria, assignor to Olympia
Werke AG, Wilhelmshaven, Germany

Filed Jan. 10, 1968, Ser. No. 10,119

Term of patent 7 years

Claims priority, application Germany Sept. 4, 1967

Int. Cl. D18—01

U.S. Cl. D64—11

Fig. 1

Fig. 2

Fig. 3

FIG. 1 is a perspective front view;
FIG. 2 is a perspective side view; and
FIG. 3 is a perspective rear view of my design.
The essential features of the design reside in the portions shown in the solid lines; conventional keys and other mechanical elements being shown in broken lines for illustrative purposes.

I claim:

The ornamental design for a housing for a typewriter, substantially as shown and described.
